SYSTEM OF CONTROL.

1,140,901.

Specification of Letters Patent.

Patented May 25, 1915.

Application filed July 2, 1913. Serial No. 777,000.

To all whom it may concern:

Be it known that I, ARTHUR J. HALL, a subject of the King of Great Britain, and a resident of Wilkinsburg, in the county of Allegheny and State of Pennsylvania, have invented a new and useful Improvement in Systems of Control, of which the following is a specification.

My invention relates to systems of control for electric motors, and it has special reference to systems that are adapted for automatic acceleration and embody means whereby the motors may be accelerated at any desired rate, irrespective of the normal operation and setting of the apparatus.

One of the objects of my invention is to provide a system of the above indicated character which shall be simple in arrangement and effective and reliable in operation.

Another object of my invention is to provide means adapted for use in an automatic multiple unit control system, which, while permitting the most economical automatic progression of the resistance-governing switches under normal operating conditions, permits of manual control of the several switches under abnormal service conditions, such as are encountered upon heavy grades, without disturbing the normal adjustment of the limit switches and circuit breakers.

A still further object of my invention is to provide means associated with a system of automatic control, whereby the several resistance-governing switches may be independently and successively closed at the will of the operator, but only one at a time and not faster than a predetermined rate, which precludes the possibility of abusing the motors by excessive accelerating currents.

A still further object of my invention is to provide a so-called "notching relay" of simple and durable construction which may be readily installed and maintained, and adjusted for any operation, irrespective of the normal setting of the limit switches.

Another object of my invention is to provide a relay for a single car equipment, or a plurality of relays for a multiple unit system, one or all of which may be governed simultaneously by the operator and actuated to short circuit the limit switches temporarily, whereby single or corresponding resistance-controlling switches may be closed independently of the limit switches.

Heretofore, railway equipments have been

provided with switches for the purpose of accomplishing somewhat similar results to those I have in view, but manually controlled devices having means for limiting the period during which the limit switch is short circuited, thus making it impossible for several resistance switches to close simultaneously or in rapid succession and subjecting the motors to excessive and injurious amounts of current, have not been employed. Furthermore, in multi-car trains, the motorman could only control the operation of the limit switch of the first car, which was entirely ineffectual in securing the desired results.

In some instances, time-limit relays have been employed which were adapted to automatically "notch up" or accelerate the motors, irrespective of the action of the limit switches. However, these devices were adapted for intermittent and continuous operation and were, therefore, subject to severe wear and operating conditions which rendered them unreliable and expensive to maintain.

My present invention is intended to obviate the difficulties encountered heretofore, and to improve and simplify the automatic control and the operation of electric motors.

In the accompanying drawings, Figure 1 is a view, partially in side elevation and partially in section, of a notching relay constructed in accordance with my invention. Fig. 2 is a view, partially in section and partially in end elevation, of the device shown in Fig. 1, and Fig. 3 is a diagrammatic view of a system of control embodying my invention.

Referring to the drawings, the device shown comprises a supporting frame 1, a valve magnet 2, an operating cylinder 3 and co-operating piston 4, and a plurality of switching devices 5 and 6 which are correlated and adapted to act in the manner hereinafter set forth.

The valve magnet 2 may be of any suitable construction such as is employed extensively in the art and comprises a stationary core 8, a movable armature 9, a plurality of oppositely disposed valve plugs 10 and 11 which are, respectively, fixed to valve stems 12 and 12^a and are adapted to co-operate respectively with valve seats 13 and 14 in the usual manner. A spring 15 normally tends to hold the valve plug 11.

2
against its seat 14, whereby the supply of operating fluid from a supply chamber 16 is shut off from the operating cylinder 3, and the valve plug 10 is maintained in its upper position to permit the escape of operating fluid to the atmosphere, as will be readily understood. The valve magnet 2 is provided with an energizing coil 17 for governing the action of the valves. It is not deemed necessary to give any further description of this portion of the device.

The operating cylinder 3 is provided with a centrally disposed guiding sleeve 18 in which a piston rod 19 is movably fitted, the lower end thereof being secured to the piston 4, in accordance with common practice. A heavy coil spring 20 surrounds the piston rod 19 and guiding sleeve 18 and acts against the piston 4 in opposition to the operating fluid to maintain it in its lowest position.

Secured to the upper end of the piston rod 19, is a bracket arm 25, the end of which carries a block 26 of insulating material to which is secured a bracket or engaging member 27, said member extending the full length thereof.

The switching device 5 comprises a stationary contact terminal 28 of substantially downwardly tapering form which is rigidly secured to a stationary supporting member 29 that is suspended suitably from the frame 1. The terminal 28 is provided with a clip 30 to which external connection is made. A rod 32 projects through openings in the engaging member 27 and stationary contact terminal 28 and is fixed to the member 27 by means of collars 33 which are disposed on each side thereof and are pinned or otherwise secured to the rod 32. A bushing 34 of insulating material surrounds the mid portion of the rod 32 and thus insulates it from the stationary contact terminal 28. Operating with the terminal 28, is a movable contact member or clip 35 of substantially U-shape that is adapted to engage the tapering surfaces of said terminal. The contact member 35 is resiliently supported upon the rod 32 by means of a coil spring 36 and the bushing 34 is secured in position against the longitudinal movement with respect to the rod 32 by means of pinned collars 37 and 38.

The switching device 6 comprises a stationary contact terminal 39 similar to that already described, but disposed oppositely thereto with its tapering surfaces projecting upwardly to cooperate with a movable contact member 40, also similar to that already set forth and held rigidly in position upon a rod 41, the upper end of which projects loosely through an opening in the engaging bracket 27. A bushing 43 of insulating material surrounds the lower end of rod 41 and insulates it from the stationary contact member 39.

65 A longitudinally slotted strap 46 consti-

tutes the middle portion of the rod 41 and, co-operating with the surface thereof, is a coil spring 47 which is held in position by means of a bolt 48 projecting through the slot 49. Near the upper end of the rod 41 and directly beneath the engaging member 27, is a fixed collar 50. A flexible conducting shunt 51 is connected between the upper ends of the rods 32 and 41, being secured thereto by a plurality of sets of nuts 52 and 53, respectively.

When the piston 4 is raised by the admission of an operating fluid to the lower portion of the cylinder 3 through the agency of the energization of the valve magnet 2, the engaging member or bracket 27 is also raised and, in turn, carries with it the rod 32, thereby causing the engagement of the co-operating contact members 28 and 35. During this movement, rod 41 and its associated movable contact member 40 remain at rest until just after the closure of contact members 28 and 35 is effected, at which time, the engaging member 27 engages the nuts 52 and effects the separation of the contact members 39 and 40. It is evident, therefore, that both switching devices 5 and 6 are closed only for a very short interval of time during the upward movement of the piston 4. The duration of concurrent closure of devices 5 and 6 may be governed by suitable adjustments of nuts 53.

When the valve magnet 2 is de-energized, the valves 10 and 11 are so arranged as to permit the escape of the operating fluid from beneath the piston 4, as will be readily understood, and thus permit the spring 20 to effect the downward movement of the bracket 25 and engaging member 27. Obviously, the member 27 carries with it the rod 32 and thus immediately disconnects the contact members 28 and 35. Since the member 27 is independent of rod 41 until it engages the collar 50, and the engagement of the contact members 39 and 40 is temporarily delayed by the frictional engagement between the spring 47 and the engagement strap 46. Manifestly, therefore, there is no time during the release of the piston 4 that both the switching devices 5 and 6 are closed.

The operation of the device may best be understood by reference to Fig. 3 which illustrates a simple control system embodying my invention. A full description of this system being unnecessary, only that portion which pertains directly to my invention will be set forth in detail.

In general, the system comprises a supply conductor marked "Trolley", a return circuit marked "Track", a plurality of motors having armatures M^1 and M^2 and field windings F^1 and F^2 , a plurality of resistors R^1 , R^2 , R^3 and R^4 having corresponding electrically-operated short-circuiting switches, a manually operated device marked "Master" 120

Controller", an electro-responsive device marked "Limit Switch", a source of control energy marked "Battery" and a switching device marked "Notching Relay".

5 In the first position of the "master controller", switch LS is energized and closed, thereby establishing a circuit from the "trolley" through switch LS, motor armature M^1 , field winding F^1 , motor armature M^2 , field winding F^2 , the energizing coil of the "limit switch", and resistors R^1 , R^2 , R^3 and R^4 to the "track". Energy is thus supplied to the motors and operation thereof is effected.

10 15 If the "master controller" be moved to its second position, the several resistors R^1 to R^4 , inclusive, will be excluded from circuit automatically and in succession, dependent upon the action of the "limit switch," 20 which, in accordance with the usual practice, is adapted to be raised under predetermined current conditions, and is permitted to drop to complete the control circuits only when the acceleration of the motors, and, consequently, 25 the counter electro-motive force thereof, is increased to a predetermined value. This portion of the system and operation will not be discussed, as such operations and circuit connections are familiar to 30 those skilled in the art.

The system so far described is adapted for normal automatic operation under the usual service conditions, but, in case of a heavy grade, it is evident that, without other provisions being made, the motor current might be sufficiently heavy to hold up the "limit switch" and thus prevent the acceleration of the motors. In order to provide for such circumstances, I employ a "notching relay" having the structural features already set forth, and I connect it in multiple circuit to the switch members 54 and 55 of the "limit switch." The multiple circuit referred to, includes, in series relation, both of the switching devices 5 and 6 which constitute parts of the notching relay. The energizing coil 17 of the valve magnet 2 is, for simplicity and clearness, illustrated as directly actuating the engaging member 27 instead of governing the operation of pneumatic actuator, as described. The coil 17 is included in a circuit containing a manually-operated switch or push button 56 which may be conveniently located on the "master controller" where it may be operated at will by the motorman.

In case a heavy grade is encountered and further automatic acceleration is impossible by reason of the normal "setting" of the "limit switch," it is only necessary for the motorman to press the push button switch 56, thus energizing the coil 17 to cause the engaging member 27 to be raised in the manner hereinbefore set forth. During this operation, as already explained, the switching

devices 5 and 6 are both closed at the same time for only a short period during which a circuit is established from one side of the "limit switch" contact members 54 and 55, through conductor 57, switching device 5, 70 shunt 51, switching device 6 and conductor 58, to the other side thereof. The "limit switch" is thus momentarily short circuited to permit the energization and closure of the proper resistance-governing switch. The period of contact is just sufficient to permit only a single switch to be actuated, so that, in order to close another switch, it is necessary to release the push button 56 and again establish a circuit through coil 17 by means 80 of it. By reason of the frictional engagement of the spring 47 and strap 48, a predetermined time interval is required for the closure of switching device 6 after the coil 17 has been deenergized, and it is therefore 85 impossible to close several resistance-governing switches in rapid succession. Thus, the motorman may accelerate the motors at will, irrespective of the setting of the "limit switch," but cannot subject the motors to 90 excessive damaging currents, as the resistance-governing switches cannot be closed except at a predetermined safe rate.

95 It will be understood that the diagram shown and described is only illustrative of a very simple system embodying my invention; and that my invention is not restricted to such a system; since it may be embodied in any of the various well-known systems that are employed for the control of electric 100 railway or vehicle motors. Furthermore, the structural features of my relay may differ materially from those set forth and I, therefore, desire that only such limitations shall be imposed as are indicated in the appended claims.

I claim as my invention:

1. A system of control, comprising a plurality of independently operated switches adapted to be automatically closed in a predetermined sequence under predetermined current conditions, and means under the control of the operator for temporarily suspending the automatic progression of the switches for a definite short interval of time. 110

115 2. A system of control, comprising a plurality of independently operated switches adapted to be automatically closed in a definite progression in accordance with predetermined current conditions, and an auxiliary manually controlled means normally independent of the operation of said switches for effecting the closure of said switches successively in a regular sequence and under limits as to closing intervals. 120

125 3. A control system for electric motors comprising a plurality of independently actuated switches adapted to be closed in a predetermined sequence, an electro-responsive device dependent upon current condi- 130

4

tions for automatically governing the progression of said switches, and manually controlled means for rendering said device inoperative for a short interval of time.

5 4. A system of control comprising a plurality of independently actuated switches, automatic means for closing said switches successively in accordance with predetermined conditions, and manually controlled 10 means normally independent of said system for effecting the closure of one switch at a time, under abnormal circuit conditions.

5 5. A system of control comprising a plurality of independently actuated switches, 15 automatic means dependent upon circuit conditions for closing said switches successively, and manually controlled means for rendering the operation non-automatic and closing a single switch.

20 6. A system of control for electric motors, comprising a plurality of independently operated switches adapted to close in predetermined sequence, a current relay for suspending the closure of said switches, and 25 means for temporarily short-circuiting said current relay for a predetermined time, at the will of the operator.

7. A system of control for electric motors, 30 comprising a plurality of independently operated switches adapted to close in predetermined sequence, a current relay for suspending the closure of said switches, and a plurality of switching devices in series circuit with each other and in multiple with 35 said current relay and adapted to be closed concurrently only for a short period of time to permit the closure of a single switch independently of said current relay.

8. A system of control for electric motors, 40 comprising a plurality of independently operated switches adapted to close in predetermined sequence, a current relay for suspending the closure of said switches, and a plurality of switching devices connected 45 in series with each other and in multiple with said current relay, manually controlled means for actuating said switching devices, and means associated with said devices for causing a single limited concurrent closure 50 of said devices corresponding to each operation of said manually controlled means.

9. A relay apparatus comprising a plurality of switching devices connected in series relation, means common to both devices for actuating the same, and means for causing both of said devices to be concurrently closed for a definite period but once corresponding to each operation of said actuating means.

60 10. A relay apparatus comprising a plurality of series connected switching devices one of which is initially open and the other closed, means for closing one of said devices just prior to the opening of the other 65 device during one direction of movement,

and means for preventing a concurrent closure of said devices during the other direction of movement.

11. A relay apparatus comprising an actuating means, a plurality of sets of co-operating switch members, one of which is normally open and the other closed, means for causing the first switch to close just prior to the opening of the second switch during one movement of said actuating means, and means for delaying the movement of one of the switch members to permit the first switch to open prior to the closure of the second switch during the other movement of the actuating means.

12. In a control system, the combination with a plurality of independently operated switches adapted to be automatically closed in a predetermined sequence in accordance with circuit conditions, of normally inoperative means independent of the automatic operation of the system and under the control of the operator for temporarily suspending the automatic progression of the switches.

13. In a control system, the combination with a plurality of independently operated switches adapted to be automatically closed in a predetermined sequence in accordance with circuit conditions, of means independent of the automatic operation of the system and adapted to be rendered operative at the will of the operator for effecting the successive closure of said switches under abnormal current conditions.

14. In a control system, the combination with a plurality of independently operated switches adapted to be automatically closed in a predetermined sequence in accordance with circuit conditions, of independent electrically controlled switching means adapted to be energized at the will of the operator for temporarily suspending the automatic operation of the system for a predetermined interval under abnormal current conditions, said means being operative but once for each energization thereof.

15. In a system of control, the combination with a plurality of independently operated switches adapted for successive operation, electro-responsive means for rendering the operation of said switches dependent upon circuit conditions, and controllable means for initiating the operation of said switches and said means, of independent means under the control of the operator for temporarily rendering said means ineffective and for effecting the closure of one of said switches under abnormal circuit conditions.

16. In a system of control, the combination with a plurality of independently operated switches adapted for successive operation, electro-responsive means for rendering the operation of said switches dependent upon circuit conditions, and controllable

means for initiating the operation of said switches and said means, of independent normally inoperative means under the control of the operator for closing said switches 5 independently of said electro-responsive means when abnormal circuit conditions obtain.

17. A system of control for electric motors, comprising a plurality of independently operated switches adapted to close in a predetermined sequence, a current relay for automatically governing the operation of said switches in accordance with current conditions, a plurality of series-related

switches connected in multiple to said automatic current relay, and controllable means for causing said switches to temporarily short-circuit said relay under abnormal load conditions, whereby the automatic operation is suspended and one of said independent switches is closed.

In testimony whereof, I have hereunto subscribed my name this 28th day of June, 1918.
